(57) **CLAIM**

The ornamental design for a garment with bandana, substantially as shown and described.

DESCRIPTION

FIG. 1 is a perspective view of the garment with banana showing the top, front and left side thereof;

FIG. 2 is a perspective view showing the top, rear and left side thereof;

FIG. 3 is a front elevation view thereof;

FIG. 4 is a rear elevation view thereof;

FIG. 5 is an elevation view of the right side thereof;

FIG. 6 is an elevation view of the left side thereof;

FIG. 7 is a top plan view thereof;

FIG. 8 is a bottom plan view thereof;

FIG. 9 is a view similar to FIG. 1 showing the bandana opened;

FIG. 10 is a view similar to FIG. 2 showing the bandana opened;

FIG. 11 is a more detailed view of the portion of the bandana noted in FIG. 2; and,

FIG. 12 is a more detailed view of the portion of the bandana noted in FIG. 4.

The broken lines on the garment with bandana represent the bounds of the claimed design, and form no part of the claimed design. The remaining broken lines represent the boundary of the enlarged view, and form no part of the claimed design.
